United States Patent Office.

H. W. LITTLE, OF MUNCIE, INDIANA.

Letters Patent No. 96,931, dated November 16, 1869.

NEEDLE-POLISHER, SHARPENER, AND LUBRICATOR.

The Schedule referred to in these Letters Patent and making part of the same.

I, H. W. LITTLE, of Muncie, county of Delaware, and State of Indiana, have invented an Improved Needle-Polisher, Sharpener, and Lubricator, of which the following is a specification.

My invention consists of a device provided with an emery-cushion, whereby the needle may be polished; a whetstone upon which it may be sharpened; and with soapstone, soap, or French chalk, with which to lubricate it.

In the accompanying drawings is represented, in—
Figure 1, a front elevation of the device.

Figure 2, a side elevation.

Figure 3, a section through line z of fig. 1.

Figure 4, a section through line z of fig. 2.

Figures 5, 6, 7, 8, and 9, are views of detached parts.

A case or frame, A, made from suitable metal, bent to proper shape, or of pieces of wood attached together, supports, centrally, between its sides, a bag, E, of emery, which protrudes through the sides of the case, they being pierced with suitable openings therefor.

The case carries, fixed in its upper end, a sand or whetstone, B, and at its lower end, a soapstone or piece of soap, D.

The purpose of the emery-cushion is to polish the needle and remove from its surface any rust or dirt

accumulated thereon, by simply passing it through the bag.

If the needle-point becomes dull, bent, or broken, it may be readily repointed upon the whet or sand-stone.

In sewing stiff or thick fabrics, lubrication of the needle is desirable. To accomplish this, I have provided one end of my device with soapstone or French chalk, with which the surface of the fabric is rubbed at the point of sewing.

The needle passes through this deposit of lubricating-substance as each stitch is made, and the frequent sticking or binding of the needle in the cloth is obviated.

I do not confine myself to the precise construction shown, as it may be varied without departing from my invention.

What I claim, is—

The within-described device, consisting of the supporting-frame A, carrying an emery-cushion, E, whet or sandstone, B, and soapstone or French chalk, D, the said parts being arranged substantially as shown and described.

H. W. LITTLE.
